(57) **CLAIM**

The ornamental design for a slab comprising particulate mineral material, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab comprising particulate mineral material, showing our new design. The depicted surface of the slab comprising particulate mineral material is flat.
